UNITED STATES PATENT OFFICE.

JOHN B. RUSS, OF SHELTON, AND CLARENCE E. SMITH, OF NAUGATUCK, CONNECTICUT, ASSIGNEES TO THE BASSETT METAL GOODS COMPANY, INC., OF DERBY, CONNECTICUT, A CORPORATION OF CONNECTICUT.

LIFT CATCH.

Application filed September 8, 1927. Serial No. 218,176.

Our invention relates to lift catches for handbags and other containers.

An object of the invention is to provide a novel and improved lift catch of this character.

Another object of the invention is to provide a lift catch in which the component parts thereof may be easily assembled by hand so that this work may be performed by the employees at their homes instead of at the factory.

Another object of the invention is to provide a lift catch which is so constructed that when open it has no uncovered upstanding parts, and when closed tightly closes the opening through which the catch member extends.

Another object of the invention is to provide a device of this character which is of strong, durable and cheap construction.

The several features of the invention, whereby the above mentioned and other objects may be attained, will be clearly understood from the following description and accompanying drawings, in which,

Figure 1 is a side view of the upper portion of a handbag to which our improved lift catch has been applied;

Fig. 2 is a longitudinal sectional view of the lift catch and a portion of the bag, the lift catch being shown in closed position;

Fig. 3 is a similar view but showing the lift catch in open position;

Fig. 4 is a view in perspective of the lift catch before it is applied to the bag; and

Figs. 5, 6 and 7 are detail views in perspective of component parts, respectively, of the lift catch.

In the drawings our improved lift catch is shown applied to a common type of handbag 2 having the usual inner and outer inverted U-shaped frame members 4 and 6 that are provided with the usual registering slots 8 for receiving the catch member of the device.

As shown, the component parts of the lift catch consist of a base 10, a lift member 12, a catch member 14, and a leaf spring 16.

The base 10 is made of sheet metal and is provided with a top wall 18 having a clearance slot 20, side walls 22, end walls 24, and depending tongues 26 for securing the base member to the outer frame member 6. The

top wall of the base has downwardly and outwardly beveled end portions 28.

The lift member 12 is made of sheet metal and is provided with a top wall 30, side walls 32, and end walls 34. The top wall of the lift member has downwardly and outwardly beveled end portions 36 corresponding to the beveled portions 28 of the top wall of the base. The outer end wall of the lift member is extended to provide a leaf 38, which is bent inwardly and upwardly to a substantially horizontal position, the end 65 of the leaf being beveled off. The lower end of this outer end wall adjacent the tongue or leaf 38 is provided with a slot 40.

The catch member 14 may be of a common construction and has its upper end riveted 70 or otherwise secured to the under side of the top wall of the lift member 12.

The leaf spring 16 has a bend 17 extending longitudinally and engaging the top wall of the lift member 12 when the latter 75 is closed. The leaf spring 16 is provided with a clearance slot 39 through which the catch member 14 extends. One end of the leaf spring is curved upwardly and its other end is slotted to provide tongues 41 that are 80 bent in opposite directions.

In assembling the parts of the lift catch, the outer securing tongue 26 is passed through the slot 40 in the end wall of the lift member 12, the upper end of the tongue 85 being enlarged to substantially the width of the slot 40 as indicated at 42, and the portions of the end wall between this enlarged end and the side walls of the base being cut away as indicated to provide clearance for 90 the leaf 38. It may be noted that this tongue and slot connection between the lift member and base provides a pivotal connection between them. The lower end of the catch member 14 is passed through the clearance 95 slot 20 in the top wall of the base. The slotted end of the leaf spring is then applied to the beveled end of the leaf 38 and the other end of the spring is snapped into position against the opposite end wall of 100 the base, the catch member 14 extending through the slot 39 in the leaf spring.

After the parts of the lift catch have been thus assembled, the tongues 26 of the base are inserted through suitable apertures in 105 the outer frame member 6 and bent in-

wardly and upwardly against the under side of the frame member in the usual manner so as to securely hold the lift catch in place.

5 With this construction it will be apparent that upon closing the lift member 12 so as to insert the catch member 14 through the slot 8 in the frame members, the spring 16 will firmly but yieldingly hold the lift member 12 down over the base 18, and upon raising the lift member 12 the spring likewise will hold the lift member in this position, the free end of the spring being shifted to opposite sides of its dead center with relation to the tongue or leaf 38 and the point of engagement of the bend 17 of the leaf spring with the top wall of the lift member. Also as the lift member approaches its open position the spring will act to snap it into 10 this position, the upward movement of the lift member being limited by the engagement of the head of the catch member with the under side of the spring as shown in Fig. 3 of the drawings. It will also be apparent that before attaching the lift catch to the bag frame the lift member, base and spring may be easily assembled by hand so that this work may be performed by the employees at their homes instead of at the 15 factory. The lift catch when in open position presents no uncovered upstanding parts that are liable to be accidentally struck by the hand of the user or accidentally bent, and when the lift member is closed the openings through which the catch member extends are tightly closed.

As will be evident to those skilled in the art, our invention permits various modifications without departing from the spirit 20 thereof or the scope of the appended claims.

What we claim is:

1. A lift catch for bags and other containers having, in combination, a base having means comprising a tongue for securing it to the container, a lift member having a slot through which said tongue extends to provide a pivotal connection to permit the lift member to be swung upwardly from and downwardly upon the base, a spring for holding the lift member in either of said positions, and a catch carried by the lift member.

2. A lift catch for bags and other containers having, in combination, a base having side and end walls and means comprising a tongue depending from one of the end walls for securing the base to the container with the lower edges of the side walls engaging the container, a lift member having a top, side and end walls, one of said end walls having a slot through which said

tongue extends to provide a pivotal connection to permit the lift member to be swung downwardly over and upwardly from said base, means comprising a spring for holding said lift member in either of said positions, and a depending catch secured to the under side of the top wall of said lift member. 65

3. A lift catch for bags and other containers having, in combination, a base having a top, side and end walls and means comprising a tongue depending from one of the end walls for securing the base to the container with the lower edges of the side walls engaging the container, a lift member having a top, side and end walls, one of said end walls having a slot through which said tongue extends to provide a pivotal connection to permit the lift member to be swung downwardly over and upwardly from said base, and having an inwardly projecting leaf arranged substantially horizontal, a leaf spring having one end abutting the inner end of said leaf and its other end abutting the opposite end wall of said base and suitably arranged to hold said lift member in either of said positions, and a depending catch secured to the under side of the top wall of said lift member, said top wall of said base having a clearance opening through which said catch member extends. 80

4. A lift catch for bags and other containers having, in combination, a base for attachment to the container, a lift member pivotally mounted on the base, a catch carried by said member, and a spring for yieldingly holding the lift member and catch in either open or closed positions, one end of said spring engaging a projection on the lift member and being suitably arranged with relation to the axis of said lift member to cause it to pass through a dead center as the lift member is moved from one to the other of said positions. 95

5. A lift catch for bags and other containers having, in combination, a base for attachment to the container, a lift member pivotally mounted on the base and having a projection, and means for yieldingly holding the lift member in either open or closed positions, said means having a portion engaging said projection on the lift member and being suitably arranged with relation to the axis of said lift member to cause said portion to pass through a dead center as the lift member is moved from one to the other of said positions. 105

In testimony whereof, we have signed our names to this specification this 29th day of August, 1927. 110
